UNITED STATES PATENT OFFICE.

WILLIAM B. HUGHES, OF CLEVELAND, OHIO.

MANUFACTURE OF GAS.

977,874.

Specification of Letters Patent.

Patented Dec. 6, 1910.

Application filed September 16, 1908. Serial No. 453,217.

To all whom it may concern:

Be it known that I, WILLIAM B. HUGHES, a citizen of the United States, residing in the city of Cleveland, county of Cuyahoga, and State of Ohio, have invented certain Improvements in the Manufacture of Gas.

The improvements of my invention contemplate the use of an economizer designed for intercepting and burning solid particles, such as carbon dust and tarry matter contained in gas, particularly as it flows from a producer to a scrubber, and in its preferred form the heat evolved is utilized for heating air and producing steam or vapor to be employed in operating the producer.

The characteristic features of the invention are embodied in the apparatus illustrated in the accompanying drawings and the following description thereof.

20 In the drawings, Figure 1 is a sectional elevation of a form of the apparatus; Fig. 2 is a sectional plan view of the same; Fig. 3 is an elevation of the top of the economizer at right angles to the view shown in Fig. 1; 25 and Fig. 4 is a sectional elevation of a modified construction.

In the form of the invention shown in Figs. 1 to 3 inclusive, a producer 1 discharges gas through a passage 2, which is 30 connected alternately with the passages 3 and 3' by a butterfly valve 4, the latter having a lever 4' for operating it. The passages 3 and 3' discharge into the respective chambers 5 and 5' above checkers or checkered 35 arches 6 and 6' contained in each chamber. Each of the chambers 5 and 5' has a space 5" between the arches in which the gas that has passed through the first arch expands with reduction of velocity and deposition of 40 solids, the deposition being facilitated by the obstruction offered by the second arch. The chambers 5 and 5' discharge below the arches through the respective passages 7 and 7' connected alternately with a passage 45 8 by a butterfly valve 9, this valve being operated by a lever 9'. The passage 8 discharges to a scrubber 10. In the tops of the 50 chambers 5 and 5' are the respective fire tube boilers 11 and 11', the boilers having the flues 11^a and 11^b and the chimneys 11^c and 11^d through which the products of combustion may pass from the respective chambers. Valves 12 and 12' are adapted for closing the chimneys 11^c and 11^d alternately, these valves being connected with the respective ends of a lever 13 having a

fulcrum 14. The boilers are connected together by pipes 15 and 15', the latter having the pipe 15" connected therewith for introducing or drawing off water. At their tops 60 the boilers have connected therewith branch pipes 16' of a main pipe 16, which delivers steam or vapor to the base of the producer under control of a valve 16''. It will be seen that the principles involved in this apparatus 65 which is described in its use for heating water may also be applied to heating air for use in the operation. A pipe 17, provided with outlets or nozzles 18, 18' and 18'', controlled by the respective valves 19, 19' and 19'', delivers air, or other suitable fluid for carrying on combustion, to the respective chambers 5 and 5'.

In operation when gas is flowing from the producer to the scrubber through either of 75 the chambers 5 and 5', the chimney leading from such chamber is closed while the chimney leading from the other chamber is open and combustion of the deposits therein is effected. The checkered arches of the chamber through which the gas is flowing act as baffles and collect matter discharged from the producer without gasification and which would otherwise pass to the scrubber, thus reducing in large measure the usual work of 80 washing. When this matter, consisting largely of carbon and tar, has accumulated in the chamber through which the gas has been flowing (the matter in the other chamber having been burned out), the valves are 85 reversed, the gas is passed through the chamber which has been cleansed and the deposits in the other chamber are ignited. The combustion thus carried on in the chambers 5 and 5' convert, or aid the gas discharged 90 from the producer in converting, the water in the boilers 11 and 11' into steam, which is carried to the producer to aid combustion 95 therein.

In the form of the invention illustrated in 100 Fig. 4, the producer 20 discharges gas through its outlet passage 21, controlled by the valve 22, to the chamber 23, with the lower part of which the passage is connected. The chamber contains the checkers or 105 checkered arches 24, 24' and 24'' above the discharge end of the passage 21 and the heater 25 above the arches, the heater being in the path of the gas flowing to the outlet passage 26 which is connected with the upper part of the chamber and in the path of 110 the products of combustion flowing to the

chimney 27 which is built upon the wall of and leads from the chamber, the chimney containing the valve 28. The chamber 23 is divided by the arches 24, 24' and 24'' into spaces or compartments 23', in each of which gas flowing through the immediately anterior arch expands with reduction of velocity and deposition of solids, which is facilitated by the baffling influence of the 10 succeeding arches. The heater has the inlet pipe 29 for delivering air or water thereto and the outlet pipe 30 for carrying the volatile products, under control of the valve 30', from the heater for use in the operations. 15 The pipe 30 is connected with a pipe 31 having passages or nozzles 32, 32', 32'' and 32''' which discharge under control of the respective valves 33, 33', 33'', and 33''', into the chamber 23, as when air is heated in the 20 heater.

In the operation of the modified construction, the valve 22 being open and 28 closed, gas flowing from the producer through the arches in the chamber is baffled and matters that have not been gasified are deposited. The valve 22 being closed and 28 being open, the deposits collected by the checkered arches are burned and the products of combustion utilized in raising the temperature 25 of the fluid in the heater, for the purposes specified.

Having described my invention, I claim:

1. The improvements in the manufacture 30 of gas, which comprise a gas producer, independent of said producer a pair of chambers

bers having valved chimneys, a passage for conveying gas from said producer, passages connected with said passage for conveying gas to the respective chambers, a reversing valve for connecting the passage from the 40 producer with the passages to the chambers respectively, passages through which said chambers discharge, a valve for alternately closing one and opening the other of said last named passages, and baffles in the 45 respective chambers between the passages thereto and therefrom.

2. The improvements in the manufacture 50 of gas, which comprise a gas producer, independent of said producer a pair of chambers having valved chimneys, passages for conveying gas from said producer to said chambers, a valve for controlling the flow from said producer to said chambers alternately, passages for conveying gas from said chambers, a valve for closing said last named 55 passages alternately, baffles in the respective chambers between the passages leading thereto and therefrom, and heaters in the respective chambers in the paths of the 60 products of combustion flowing to said chimneys.

In witness whereof I have hereunto set my name this 11th day of September A. D. 1908, in the presence of the subscribing witnesses. 65

WM. B. HUGHES.
